Primary Examiner — Doris Clark*(74) Attorney, Agent, or Firm* — Senniger Powers LLP**CLAIM**

The ornamental design for a molded polymeric drip edge, as shown and described.

DESCRIPTION

FIG. 1 is a perspective view of a molded polymeric drip edge having an adhesive layer and a release sheet;

FIG. 2 is a top view thereof;

FIG. 3 is a left side view of the molded polymeric drip edge, the right side view being a mirror image thereof;

FIG. 4 is a front view of the molded polymeric drip edge; and,

FIG. 5 is a rear view thereof.
